(57) **CLAIM**

The ornamental design for a portable electric cutter, as shown and described.

DESCRIPTION

FIG. 1 is a front, left and top perspective view of a portable electric cutter showing our new design;

FIG. 2 is a rear, right and bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a front, left and top perspective view of the portable electric cutter in accordance with our new design illustrating a state in which an environmental structure (a battery) is attached to the portable electric cutter.

The broken lines in the drawings illustrate the environmental structures or portions of the portable electric cutter which form no part of the claimed design.

1 Claim, 9 Drawing Sheets
